THEODORE D. HAEHNLEN, OF PHILADELPHIA, PENNSYLVANIA.

Letters Patent No. 73,098, dated January 7, 1868.

RECIPROCATING-BALL TOY.

The Schedule referred to in these Letters Patent and making part of the same.

TO ALL WHOM IT MAY CONCERN:

Be it known that I, THEODORE D. HAEHNLEN, of the city and county of Philadelphia, and State of Pennsylvania, have invented a new and useful Toy, which I denominate a Ring and Reciprocating Ball; and I do hereby declare the following to be a clear and exact description of the nature thereof, sufficient to enable others skilled in the art to which my invention appertains to fully understand and use the same, reference being had to the accompanying drawings, making part of this specification, in which—

Figure 1 is an elevation of the toy illustrating my invention.

Figure 2 is a side elevation thereof.

Figure 3 is an elevation illustrating the motion of the ball.

Similar letters of reference indicate corresponding parts in the several figures.

My invention is a new and interesting toy, and consists in applying a ring of suitable size to a handle, from which is suspended, by an elastic cord, an ordinary ball of wood or otherwise, and by a peculiar motion of the hand, the ball is sprung or thrown upward so as to pass through the ring and then fall to the full length of the cord, and then, by the elasticity of the latter, to return in the same way back through the ring to its normal position, ready to undergo the operation as often as is desired.

The entire operation requires considerable practice and dexterity, and will be found to be quite a test, but really amusing and interesting.

In the drawings, A represents a ring, of suitable size, made of proper material, by preference of metal wire, bent in annular shape, having its ends twisted to form a tang to enter a handle, B, of usual construction, and thus securely connect the ring to the handle; or the ring may be secured by a staple, or the ring and handle be cast in one piece. An ordinary thimble or ferrule, a, serves to prevent the tang from slipping out of its socket in the handle, and is in general use for such purpose. At one part of the handle, which I denominate the lower side, and near the thimble a, I secure one end of an elastic cord, C, which shall be sufficiently long, and have its other end secured to a ball, D. This ball may be made of any material, but by preference of wood, and be connected to the cord by a small staple, plug, or any other proper means of fastening.

It will be noticed that the ring lies in a horizontal direction while the ball is suspended from the handle.

The operation is as follows: The handle being grasped, so that the ring shall lie in a horizontal line, the ball will be suspended from the lower side of the handle by the elastic cord, and be in a state of rest. A slight upward twist or jerk of the hand will serve to raise the ball and contract the elastic cord, and if the hand is steady and the ball rises in a truly vertical line, or at right angles with the handle, it will pass through the ring, then fall over its sides to the length of the cord, which will be expanded relatively to the gravity of the ball. When the limit of expansion is reached, the cord contracts and raises the ball, and causes it to return to its first position through the ring, ready to repeat the operation. A practised or accustomed hand will cause the ball to make the motion stated without scarcely moving his hand or the ring, so that the latter will be in line for the ball to pass through it. A slight but uniform up-and-down swaying motion is sufficient to communicate the proper momentum to the ball. All sudden or irregular swinging of the handle will cause the ball to fly away from the ring. If the ring is caused to follow the ball, it will invariably strike the ball, and thereby lessen the chances of accomplishing the result intended.

A modification of the above is by throwing the ball upwards, past the ring, and causing it to fall through it in its descent, and then to return again to its first position. The cord may be secured to the ring directly, and the latter be held by the fingers, but as the handle is a great convenience, I prefer to use it, as is shown and described.

An interesting and somewhat scientific toy is thus produced, and one requiring considerable practice and patience to manoeuvre.

Having thus described my invention, what I claim as new, and desire to secure by Letters Patent, is—

The combination of the ring A, the elastic cord C, the ball D, and handle B, substantially as specified.

To the above I have signed my name, this 21st day of November, 1867.

THEODORE DORNEY HAEHNLEN.
